UNITED STATES PATENT OFFICE.

HENRY WEBB HYDE, OF NORTH COHASSET, MASSACHUSETTS, ASSIGNOR TO HYDE ENGINEERING COMPANY, OF BOSTON, MASSACHUSETTS, A CORPORATION OF MASSACHUSETTS.

SPRING SUSPENSION FOR VEHICLES.

Application filed January 15, 1925. Serial No. 2,636.

This invention relates to vehicle spring suspensions of the general type shown and described in my prior application for Letters Patent, filed September 29, 1921, Serial No. 504,160, and terminating in Patent No. 1,524,437 of which the present case is a continuation in part and with respect to such subject matter as it has in common therewith.

As explained in said prior application, the invention therein shown consists primarily in providing the vehicle with longitudinal springs or spring reaches connected at their ends, either directly or indirectly, with the axles, and in supporting the body on the spring reaches intermediate the ends of the latter in such a manner as to permit said body to rock freely, with respect to and independently of the reaches, upon a horizontal, transverse axis, so that tilting or rocking of the reaches, caused by a vertical movement of either the front or rear wheels and the axle carried thereby, will not be transmitted to the body and will not tend to tip or pitch the same, said body being permitted, by rocking about its axis with respect to the reaches, to maintain its substantially horizontal position, its only movement being a slight vertical one in a substantially rectilinear direction.

The present case relates to a form of spring suspension of the type above referred to, wherein resilient portions of the spring reaches are extended beyond the axles and are connected at their outer ends with the ends of the body to form balancing springs for the latter. In accordance with the preferred form of the invention, this arrangement is employed at both ends of the suspension, thereby providing, in a simple construction employing a minimum number of parts, balancing springs for both ends of the vehicle in accordance with the general principles explained in another application, filed April 23, 1924, Serial No. 708,430.

The more particular objects of the invention, together with means whereby the same may be carried into effect, will best be understood from the following description of certain forms or embodiments thereof illustrated in the accompanying drawings. It will be understood, however, that the particular constructions described and shown have been chosen for illustrative purposes merely, and that the invention, as defined

by the claims hereunto appended, may be otherwise practised without departure from its spirit and scope.

In said drawings:

Fig. 1 is a side elevation of a spring suspension constructed in accordance with the invention.

Fig. 2 is a plan view thereof, certain parts being partly broken away in order to illustrate the construction more clearly.

Fig. 3 is a view similar to Fig. 1, illustrating a modification.

The principle of operation of a spring suspension of the general type of that to which the present case relates is fully explained in my prior application, Serial No. 504,160 which terminated in Patent No. 1,524,437. For the purposes of the present description this principle may be briefly outlined as follows:

In the ordinary vehicle, whether provided with elliptical, semi-elliptical, or cantilever springs, the springs are, in effect, rigidly secured to the body or frame, and any shock or blow on a wheel, due to unevenness in the road, which causes the wheel to rise or fall suddenly, is communicated directly to the body.

In the type of spring suspension to which the present invention relates, on the contrary, if the front wheel, for example, be raised, owing to an unevenness in the road, the tendency is for the spring reach to turn about the pivot afforded by the rocker on which the body is supported, but not to rock the body. It thus tends to swing the rear end of the reach and rear axle downward about the pivot, so that the chief effect of the blow is absorbed by the rear spring and pneumatic tire on the rear wheel. Likewise, when the rear wheel goes over an obstruction or drops into a hole, the front spring member and front wheel receive the major part of the reaction and the body is affected relatively little. In any event, any vertical force, or the resultant of such vertical forces as may be transmitted to the body as a result of the rocking of the reaches, is applied to the body at the center of gravity thereof, so that there is no gyroscopic force acting upon the body eccentric to its center of gravity. The effect on the body is merely to lift the pivot, and consequently the body, vertically to a slight extent, and not to rock said body from front to

back, so that the body is not given any pitching motion. The action described is permitted by the pivotal or rocking connection between the body and the spring reaches. 5 If there were a rigid connection at this point, the blow would give the body an entirely different movement and would not be absorbed by the opposite end of the spring reach.

10 Referring now to the drawings, there is shown in Figures 1 and 2 a pair of spring reaches to which the body frame 10 is connected by means of coaxial pivots 11 interposed between brackets 12 and 13 bolted or otherwise secured to said body and reaches respectively. Each of said reaches is composed of a substantially rigid beam 14 having leaf spring extensions 15 and 15^a at its front and rear ends, respectively, each of 15 said extensions being composed of a suitable number of super-imposed leaves. The bottom leaf 21 of each of the forward extensions 15 is bolted or otherwise secured to the front axle 16; as shown at 22, and is extended 20 beyond the same and connected at its outer or forward end by a shackle 17 to the front end of the body frame 10. The bottom leaf 23 of each of the rear spring extensions 15^a is supported by a hanger 18 from the rear 25 axle 19, being, as in the case of the forward extensions, extended beyond said hanger and axle, as shown at 24; and connected at its outer or rear end by a shackle 20 with the rear end of the body frame 10. If desired, 30 particularly when the pivotal axis 11 is disposed forward of the center of gravity of the body, as in the construction shown in Figures 1 and 2, the extended bottom leaves 23 of the rear spring extensions 15^a may be 35 reinforced by additional leaves 25 in order to give the rear balancing springs 24 the requisite strength to offset the eccentric loading.

35 In the construction shown in Figure 3, as in that first described, the body frame 30 is connected by coaxial pivots 31 with central beam portions 32 of spring reaches having front and rear leaf spring extensions 33 and 34, the lowermost leaves 35 and 36 of which 40 are suitably connected to the front and rear axles 37 and 38, respectively, and are extended beyond the same and connected at their ends with the ends of the body frame. 45 As shown in this figure, the pivotal axis 31 is substantially under the center of gravity of the body. At its forward end the construction is substantially the same as that first described, with the exception that the spring extensions are pivotally connected, as at 39, to the body frame instead of employing shackles at these points. Also at the rear the extended leaves 36 of the rear spring extensions 34 are supported by hangers 40 from the rear axle 38 and are pivotally connected, as at 41, to the rear end of the body 50 frame. Interposed between each extended leaf 36 and its supporting hanger 40 are reinforcing leaves 43 which, in this form of the invention, are of a sufficient number to form, with the leaf 36, what is, in effect, a semi-elliptical spring supported from the axle 38. Also, in this construction the leaf 42 of each spring extension 34 immediately adjacent the leaf 36 is curved upwardly 55 at its rear or outer end, while the adjacent leaf 43 is curved downwardly at its forward or inner end. These oppositely curved ends of the leaves 42 and 43 provide, in effect, a rolling engagement of said leaves upon one another, notwithstanding the intermediate leaf 36, thereby permitting the effective points of operative connection between these members to vary automatically as the load on the vehicle varies, so as to preserve more 60 accurately the balance of the parts, in accordance with the principle more fully explained in another application, filed April 23, 1924, Serial No. 708,429.

65 In the form of the invention shown in Figures 1 and 2, and at the forward end of that shown in Figure 3, the balancing springs afforded by the extended ends of the reaches are relatively light and of sufficient strength only to counterbalance the eccentric loading of the vehicle, so as not in any way to interfere with the free rocking movement between the body and the reaches, and the consequent operation of the suspension in accordance with the principles above explained. 70 The arrangement shown at the rear of the vehicle in Figure 3 is such as to cause an upward force to be exerted upon the rear of the body when the front axle is raised, in accordance with the principle more fully explained in my application, filed May 28, 1923, Serial No. 641,933.

75 In this specification, the phrase "spring reaches" is employed as a comprehensive term to denote longitudinal members through which the body is supported from the axles and composed wholly or in part of springs. The term, therefore, is to be taken as including a continuous spring as well as a reach composed of a substantially rigid beam having spring extensions at its 80 ends. It will be understood that when the spring reach is constructed as last described, and as herein shown, the connection between the beam and the springs is a rigid one in the sense that there is no pivotal or other movable connection at this point.

85 The words "rear," "front," and similar expressions are herein used as convenient illustrative terms, it being obvious that, although the constructions shown are preferred for most purposes, the suspension might be oppositely disposed, the pivotal connection between the body and the reaches being, in the case of the form shown in Figures 1 and 2, in the rear instead of in 90

front of the center of gravity of the body, and the front and rear constructions being otherwise transposed in both forms. These and other modifications of the constructions 5 shown will, however, be readily apparent to those skilled in the art without further description in detail.

Having thus described my invention, I claim:

- 10 1. In a vehicle having a body and axles, a spring suspension comprising a pair of spring reaches connected with the axles and a connection between said reaches and the body upon which the latter is free to rock with respect to the former, said reaches having, at both ends of the vehicle, extensions connected at their ends with the body to constitute balancing springs.
- 15 2. In a vehicle having a body and axles, a spring suspension comprising a pair of spring reaches connected with the axles and a connection between said reaches and the

body upon which the latter is free to rock with respect to the former, said reaches each having portions composed of a plurality of leaves, at least one leaf of each reach being extended beyond the others and connected at its end with the body to constitute a balancing spring.

3. In a vehicle having a body and axles, 30 a spring suspension comprising a pair of spring reaches connected with the axles and a connection between said reaches and the body upon which the latter is free to rock with respect to the former, said reaches each having portions composed of a plurality of leaves, one leaf at each end of each reach being extended beyond the adjacent axle and connected at its end with the body to constitute a balancing spring. 40

In testimony whereof I affix my signature.

HENRY WEBB HYDE.
